UNITED STATES PATENT OFFICE.

ROY W. CUMMINGS AND ISAAC KIRBY, OF LOS ANGELES, CALIFORNIA.

AUTOMATIC VALVE.

1,087,108.

Specification of Letters Patent. Patented Feb. 17, 1914.

Application filed July 27, 1912. Serial No. 711,889.

To all whom it may concern:

Be it known that we, ROY W. CUMMINGS and ISAAC KIRBY, citizens of the United States, residing at Los Angeles, in the county of Los Angeles and State of California, have invented certain new and useful Improvements in Automatic Valves, of which the following is a specification.

This invention relates to valves, and has for its object the provision of simple and efficient means whereby the flow of fluid fuel employed to heat a liquid will be automatically set up or arrested as the flow of the liquid to be heated is set up or arrested.

15 A secondary object of the invention is to provide a device for the stated purpose which will be composed of few parts compactly arranged and capable of being rapidly and easily assembled and disassembled.

20 The invention is illustrated in the accompanying drawings and will be hereinafter fully described, the novel features being subsequently pointed out in the appended claim.

25 In the drawings:—Figure 1 is an elevation of a valve embodying our present invention; Fig. 2 is a vertical section of the same; Fig. 3 is a top plan view thereof.

For convenience of reference, we will describe the invention as embodied in a valve fitted to an apparatus in which oil is employed as a fuel for heating water.

In carrying out the invention, we employ a casing comprising an upper or water head 1 and a lower or oil head 2 which are substantially cylindrical in form and provided each with an offset or elbow 3. The upper portion of the water head is upwardly and inwardly beveled or tapered, as shown at 4, to provide a seat for the valve 5, and above this valve seat the said head is constructed with a cylindrical terminal 6 which is adapted to be secured to the water supply pipe. The offset 3 of the water head 45 constitutes the outlet of the same and is internally threaded to facilitate its attachment to a supply pipe leading to a boiler or other receptacle. The valve 5 is secured to the upper end of a valve stem or rod 7 which extends downwardly through a partition and guide 8 which is disposed between the meeting ends of the two heads and is constructed to fill the said ends as clearly shown in Fig. 2. This partition and guide 55 is provided with a central opening or passage to accommodate the valve stem or rod

7 and a packing 9 is preferably fitted within the said passage around the valve stem to prevent leakage of water therethrough.

The offset 3 of the oil head constitutes the outlet for the same and is internally threaded to facilitate its attachment to a burner-feeding pipe. A port 10 is formed in the lower wall of the bore of the oil head and immediately below the said port the said head is constructed with the upwardly inclined wall 11 constituting a seat for the lower valve 12 which is secured upon the lower extremity of the valve stem or rod 7, as clearly shown. Below the said valve seat, the oil head is constructed with a cylindrical terminal 13 which is adapted to be secured to a pipe leading from a source of oil supply. A spring 14 is coiled around the stem valve between the guide and partition 8 and the upper valve 5 and is normally expanded so as to hold the two valves raised and against their respective seats. The heads are constructed externally with diametrically opposite sleeves or cylindrical lugs 15 through which securing bolts 16 are passed to firmly hold the two heads against the central annular flange 17 of the guide and partition 8. When the securing nuts 18 upon these bolts 16 are turned home, the two heads will be caused to firmly clamp the partition and guide so that the several parts will be held together in their operative position and leakage of the fluids will be prevented.

90 The operation of the device is believed to be obvious from the foregoing description, taken in connection with the accompanying drawings.

The water enters the upper end of the water head and plays upon the valve 5 against the tension of the spring 14 so that, when the water is turned on and the pressure consequently overcomes the tension of the spring, the valve will be opened or moved downwardly so as to permit the water to flow into the boiler or other receptacle. The downward movement of the valve 5 will be transmitted directly through the valve stem or rod 7 to the oil valve 12 and the said valve will consequently be moved away from its seat so that the oil will be permitted to flow to the burner. When the flow of water is arrested at the point of use the pressure upon the two sides of the valve 5 will be equalized and the spring 14 will then be free to act so

that it will close the said valve and simultaneously reduce the flow of oil to the burner. When water is again drawn from the receptacle or boiler, the force of the spring 5 upon the upper valve will be overcome by the pressure of the water and the flow of the water and the oil will be again set up.

Our device is exceedingly simple in its construction and the arrangement of its 10 parts and may be manufactured at a slight cost. As all of the parts are inclosed, the liability of any of the working elements becoming injured or getting out of order is reduced to a minimum, and, as the valves 15 are directly connected, the simultaneous operation of the same will be insured under all conditions. Both valves are threaded onto the valve stem, as shown, and consequently may be easily removed from the 20 same so as to permit the disassembling of the device or the assembling of the same, as will be readily understood. As the two heads are held together against the central partition and guide by bolts inserted 25 through sleeves disposed at diametrically opposite points of the heads and preferably formed integral therewith the parts will be positively held in their proper operative positions. The valve seats are formed integral 30 with the respective heads and consequently cannot shift relative to the heads so that the proper engagement of the valves and the valve seats will be assured.

It will be observed that the disks or valves 35 are threaded onto the ends of the valve rod so that, if the water supply is irregular and the flow fluctuates, the valves may be adjusted so that the oil valve will be held slightly away from its seat instead of resting 40 tightly against the same and a small stream of oil will be permitted to flow to the burner at all times unless the flow is shut off somewhere in the inlet pipe. This adjustment will prevent the extinguishment of the fire if the water should cease to flow. If, under

a fluctuation of the water pressure, the water valve should seat and the oil valve be permitted to tightly engage its seat, when the water again started to flow, the oil valve would be opened and the oil would then 50 again flow to the burner and would flood the burner and be lost besides tending to damage parts adjacent the burner besides causing a waste of oil. When the water pressure is steady, the valves will be adjusted so that both will seat. Should the oil 55 pressure rise abnormally, it will close the oil valve against the pressure of the water on the water valve and thereby prevent flooding of the burner and the consequent irregularity in the flame.

What we claim is:—

A device for the purpose set forth comprising an upper head having an inlet port at its upper end and having a lateral offset 65 constituting an outlet port and provided internally between its upper end and the said offset with an annular valve seat, a lower head having an open lower end and having a lateral offset providing an outlet 70 port, a support fitted in the lower end of the upper head and the upper end of the lower head and closing the same, the lower head being provided below the lateral offset with an internal annular beveled projection 75 forming a valve seat, a valve rod extending through the said support and having its ends disposed concentrically with the said valve seats and its lower end extending below the internal annular projection on the lower head, and valve disks secured upon the ends of the said rod and adapted to engage the said valve seats.

In testimony whereof we affix our signatures in presence of two witnesses.

ROY W. CUMMINGS. [L.S.]
ISAAC KIRBY. [L.S.]
